UNITED STATES PATENT OFFICE.

WILLIAM H. H. AYARS, OF INDIANAPOLIS, INDIANA, ASSIGNOR OF ONE-HALF
TO JOHN C. ERTEL, OF SAME PLACE.

NUT-LOCK.

SPECIFICATION forming part of Letters Patent No. 394,749, dated December 18, 1888.

Application filed May 8, 1888. Serial No. 273,252. (No model.)

To all whom it may concern:

Be it known that I, WILLIAM H. H. AYARS, a citizen of the United States, residing at Indianapolis, in the county of Marion and State 5 of Indiana, have invented certain new and useful Improvements in Nut-Locks, of which the following is a specification.

The object of my said invention is to produce an efficient lock for one or more nuts 10 after they have been turned up to place on the bolts on which they are used. Said lock consists in the peculiar construction and arrangement hereinafter more particularly described and claimed.

15 Referring to the accompanying drawings, which are made a part hereof, and on which similar letters of reference indicate similar parts, Figure 1 is a perspective view of the ends of two railroad-rails secured together in 20 the ordinary manner and the nuts locked in position by means of my invention; Fig. 2, a side elevation of the same, the bolts and nuts, and also the stud carrying the locking-plates, being cut in section, as indicated by the dotted line 2 2 in Fig. 3; Fig. 3, a horizontal sectional view on the dotted line 3 3 in Fig. 2, and Fig. 4 a detail view of one of the locking-plates separately.

In said drawings, the portions marked A 25 represent the railroad-rails; B, the fish-plates by which said rails are connected; C, the bolts which pass through said rails and said fish-plates; D, a long washer, which I prefer to use as a base for the locking-plates, which 30 constitute the principal feature of my invention, (although said plates may be mounted directly on the fish-plates;) and E, said locking-plates.

The rails, fish-plates, and bolts are of course 40 of the ordinary or any desired construction and need no special description herein, and I may here remark that this invention is not confined to railroad uses, and consequently any other construction showing the bolts and 45 nuts in position where the nuts may be locked is equally within the scope of my invention.

As before stated, I prefer to use the long washer D, which extends over the several bolts and lies against the fish-plates; but instead 50 of the studs d, upon which the locking-plates are mounted, might be formed directly

on the fish-plates or secured thereto without departing from my invention. However, by using the separate washer, as shown, the invention may be applied to joints already in 55 use without any labor, except that incident to placing the lock in position.

The locking-plates E are simply plain metallic plates having longitudinal slots, as shown, and notches extending toward one side 60 from said slots, which are adapted to slip down over the studs d and lock the plates in position. The ends of these plates, which rest against the nuts, may be turned up, if desired.

65 The method of applying my invention is as follows: The nuts being removed, the washer D, carrying the locking-plates, is placed over the ends of the bolts, the locking-plates being arranged centrally between said bolts. The 70 locking-plates are slipped out toward said nuts, and, being so constructed that when their ends come against the faces on the nuts the notches in the slots will just register with the studs on which said plates are mounted, 75 they then drop down, so that said notches pass over said studs, whereby they are held in position, and the nuts then cannot work or be turned off until said plates are raised up and slipped back away from them. In order 80 that the plates may be held firmly in their position against the nuts, said nuts may, after they have been so placed, be given a slight backward turn, which will bring them forcibly against the ends of the plates, which will 85 then be securely held, as will be readily understood. This may be aided by recessing the end of the plates slightly, as shown most plainly in Fig. 4, so that the corner of the nuts 90 may engage with the slight projections thus formed.

95 Of course it will be readily understood that when there is but one nut to lock but one of the locking-plates will be necessary, and also, while I have illustrated the lock in connection with a railroad-rail and its nuts, yet it is equally as serviceable in locking many other kinds of nuts in connection with other mechanism, the lock constituting the invention independently of any particular variety of mechanism on which it may be used.

100 Having thus fully described my said inven-

tion, what I claim as new, and desire to secure by Letters Patent, is—

- 5 1. The combination, with a bolt and its nut, of a locking-plate having a longitudinal slot with a notch or offset at one side, and a stud adjacent to said nut, upon which said locking-plate is mounted and over which it is permitted, by means of said slot, to slide toward and from the nut in the operation of locking 10 and unlocking the same, and said notch or offset being adapted to fit over said stud, whereby said plate may be secured from sliding thereon when in position to lock the nut, substantially as set forth.
- 15 2. The combination of a long washer adapted to fit over the ends of bolts and pro-

vided with a stud between said bolts, and two locking-plates mounted upon said stud, each of which is provided with a longitudinal slot having a notch in one side, said plates being 20 adapted to be moved first against the sides of the nuts and then down, so that the notches therein will engage with the stud and hold them in that position, substantially as set forth. 25

In witness whereof I have hereunto set my hand and seal, at Indianapolis, Indiana, this 4th day of May, A. D. 1888.

W. H. H. AYARS. [L. S.]
